EXCAVATING DIPPER

Mitchell L. Fykse, South Milwaukee, Wis., assignor to Bucyrus-Erie Company, South Milwaukee, Wis., a corporation of Delaware

Application March 16, 1936, Serial No. 69,171

17 Claims. (Cl. 214—145)

My invention relates to new and useful improvements in excavating dippers, such as are carried on handles, reciprocable in and rotatable with saddle blocks, carried on inclined booms of the well-known power shovels.

5 The actual breaking up of the material to be dug is accomplished by the "lip", or upper edge, of the dipper front, the lip being furnished with replaceable teeth, to aid in the disintegration of the material. The lip is naturally subject to 10 very great wear, and must therefore be made of some high grade wear-resisting material, such as manganese steel. But even if made of the very best material, the front of the dipper, and particularly the lip, will wear out sufficiently to 15 reduce materially the efficiency of the excavator long before the other parts of the dipper need to be replaced.

To provide the possibility of replacing a front without replacing the whole dipper,—which latter 20 would be prohibitively expensive—manufacturers have been casting their dippers in two separate parts: (1) a front half (or upper half, or upper front quadrant) of high grade material; and (2) a rear half (or bottom half, or lower rear three 25 quadrants) of less expensive material: the two parts being bolted, or otherwise secured together, in such a manner that, when the digging part is worn beyond the point of economical use, it may be replaced by a new such part.

30 The weight of the digging part usually approximates one-half that of the whole dipper, so that replacing this part by another of high grade material is quite expensive, especially as it is only the lip portion of this part that requires high quality 35 material, as the wear on the rest of this part is much less than that on the lip. Some manufacturers are attempting to eliminate the needless expense of making the whole of this part of high grade material, by placing, on a medium grade 40 front half or upper half, a separate, replaceable lip-piece. This expedient has, however, some undesirable features. Such a lip-piece, by requiring various lugs, bolts, etc., to join it to the back and to the remainder of the front, adds considerable to the total weight, and therefore to the 45 cost. Furthermore it has been found difficult to connect the lip portion sturdily enough to the remainder of the dipper.

It is the principal object of my invention to 50 reduce these costs, and to increase strength, without sacrificing easy replaceability. This I accomplish as follows:

Instead of casting all portions of the dipper, I 55 cast only the lip proper, with a narrow Y-shaped extension running to the bottom of the dipper.

I make the back and sides and the lower portions of the front of my dipper, of plate material, bent to shape; as the stresses in, and wear on, these portions are relatively small. My lip portion is so attached as to be easily replaceable.

Another object of my invention is to provide 5 for the possibility of using the same dipper on any one of a number of different types of handles, as I provide vertical ribbing, which may be spaced on the back to suit the particular handle, being 10 welded into proper place to fit the requirements of the handle.

As is usual in digging dippers, I provide my lip portion with sockets, for the insertion of teeth. The lip has upward projections that fit into the 15 sides of the teeth, thus providing supports for the teeth that are far up towards their cutting edge, and thereby reducing stresses that tend to cause breakage. This feature of my invention is covered by the copending application of myself and 20 Mark J. Woodhull, Serial No. 717,002, filed March 23, 1934, for improvements in dipper teeth, which has since matured into Patent No. 2,040,085, dated May 12, 1936.

I have provided convenient means for the attachment of a bail, this means also serving to 25 help lock my lip portion to the dipper, and to transmit the hoisting pull directly to the lip portion.

I also construct all parts of my dipper so as to 30 have smooth inside surfaces with no inside splices between the portions. This ensures better dumping.

In addition to the objects stated, I have worked out a number of novel and useful details, which 35 will be readily evident from the description which follows.

My invention consists in the novel parts, and in the combinations and arrangements thereof, which are defined in the appended claims; and 40 of which one embodiment is exemplified in the accompanying drawing, which are hereinafter particularly described and explained.

Throughout the description, the same reference number is applied to the same member or to 45 similar members.

Referring to the drawing, it will be seen that Figure 1 shows a side elevation of my dipper.

Figure 2 is a front elevation, also showing one tooth in place.

Figure 3 is a vertical section through the cast front, and through a tooth, taken as indicated by the line 3—3 in Figure 2, and showing the manner in which the tooth is secured in the socket.

Figure 4 is a vertical section taken as indicated 50 by the line 4—4 in Figure 2.

Figure 5 is a vertical section taken as indicated by the line 5—5 in Figure 1.

Figure 6 is a vertical section taken as indicated by the line 6—6 in Figure 7.

5 Figure 7 is a slightly enlarged and slightly more detailed showing of the bail attachment of Figure 1.

Figure 8 is a horizontal section taken as indicated by the line 8—8 in Figure 7.

10 Referring more particularly to Figures 1 and 2, we see that 11 is a plate, bent to form the back and sides and a portion of the front, of my dipper. This plate is symmetrical about a vertical line through the center of the back, and is of 15 such a shape that, when the ends are brought around to the middle of the front, as indicated in Figure 2, where they may be joined by a weld (which for simplicity is not shown), their upper edges 12 form an open V, which is to be filled by 20 the cast front 13.

The front 13 is provided with sockets 14, for the insertion of teeth 15, each of which is secured in place by a taper-pin 16, driven through aligned holes 17 in the dipper front and a corresponding 25 hole 17a in the tooth base, as shown more particularly in Figure 3.

The lip 18, i. e. the upper edge of the front 13, has, at each tooth socket, upward projections 19 that fit into the sides of the teeth 15, thus providing supports for the teeth as near the cutting edge as possible, and correspondingly reducing the risk of breakage. This feature is covered by the copending application already referred to herein.

35 The cast front 13 is Y-shaped, as seen in Figure 2, to overlap the V-shaped opening formed by the joining of the two ends of the plate 11, and is joined to the plate 11 by bolts or rivets 20.

At 21 is shown a combined latch-keeper and 40 splice-plate, which cooperates with the latch-bar 22 (Figure 4) to latch the dipper-door 23, the door being hinged at 24 to an element later to be described. By means of bolts 25 this latch-keeper 21 binds the two ends of plate 11 (bent around 45 and welded together as before described) to a relatively narrow downward prolongation 26 of the cast front 13, which is shown in section in Figure 4, and to a bottom-bar 27. The bottom-bar serves to strengthen the lower portion of the 50 dipper, being bolted, welded, or otherwise secured thereto.

The cast front 13 is strengthened by vertical and horizontal flanges 28, 29, respectively.

An upper reinforcement 30 and a similar lower 55 reinforcement 31, each shaped to fit against the back and a portion of the sides as shown, are welded on the plate member 11.

Four or more dipper-back ribs 32 are welded or 60 otherwise secured to the back of the dipper, and to the upper and lower reinforcements 30, 31. These ribs are vertical and parallel, and are spaced to suit the requirements of the particular handle to which the dipper is to be attached.

65 Thus at 33 is shown one of the two handle-attachment pins, which passes through aligned holes in two adjacent dipper-back ribs, and through one of the two side-pieces of the handle (not shown). Similarly passing through aligned holes in two adjacent dipper-back ribs 32, is shown one of the two handle-brace pins 34, which serve to 70 attach the handle-brace (not shown) to the dipper. If the dipper is to have a padlock-sheave attached to the back, rather than to the 75 bail-lugs hereinafter described, corresponding

holes for a padlock-pin 35 are provided in the central ribs.

5 My method of mounting the dipper on the handle presents the following advantage over the older construction. The dipper-back being straight and of uniform cross-section, and the reinforcements 30, 31 each having uniform cross-section throughout, all vertical sections through the back are exactly similar. Hence the dipper-back ribs 32 may be left off until the dimensions 10 of the particular handle upon which the dipper is to be used are known, and then welded on, spaced accordingly. Thus, of several dippers, exactly alike in all other respects, each may be placed on a handle the dimensions of whose end 15 differ from the corresponding dimensions of any of the other handles.

If the dipper is to have a bail, a hole is drilled 20 through the rearwardly projecting side portion of the cast front 13, and corresponding holes in the side piece 11 and the reinforcement 30, the latter two holes being slightly larger than the former, in order to avoid the necessity of securing very exact alignment. A shear-plug 36, having a hole 25 for a bail pin 37, is then close-fitted in the hole in Figures 6 and 8 to the side-piece 11 and reinforcement 30; any slight difference in alignment being taken up by the welding.

Let us now consider the bail-bracket 39, which 30 plays an important part in my invention. As clearly indicated in Figures 6 and 7, the rearwardly projecting portion of my cast front 13 overlaps and clears my side-piece 11 and my reinforcement 30, and also extends slightly further 35 downward than my reinforcement 30. The shoulder 40 (see Figure 7) and lower edge 41 (see Figure 6) of this rearwardly projecting portion constitute two abutments at right angles to each other. The bail bracket 39 is built with cooperating abutments, and is secured (as by rivets 42) to the side-piece, and (as by rivets 43) to the front.

The result of this construction is that the 45 hoisting strain, during digging, is directly applied to the front 13, thus eliminating any appreciable tendency to shear either the bail-bracket 39 or the reinforcement 30 from the other parts of the assembly.

The ball-pin 37 may be secured against rotation and translation by any appropriate means, such as a set-screw 44. The bail (not shown) is pivoted in the usual manner on the bail-pin 37.

For a dipper without a bail, the shear plug 36 described above is replaced by a solid plug, similarly welded in place.

Having now described and illustrated one form of my invention, I wish it to be understood that my invention is not to be limited to the specific form or arrangement of parts hereinbefore described, except insofar as such limitations are specified in the appended claims.

I claim:

1. In an excavating dipper, the combination 65 of: a vest-shaped piece of plate-metal, bent to form the back, the two sides and the front of the dipper; a Y-shaped casting, forming the upper portion of the front, and constituting a juncture for the vest-shaped piece, and having bent-around portions for the reinforcement of a portion of the upper part of the sides; and a plurality of metal vertical ribs, attached to the back of the dipper, to constitute means of attachment, and to constitute a reinforcement for the back. 70 75 75

2. In an excavating dipper, the combination of: a vest-shaped piece of plate-metal, bent to form the back, the two sides and the front of the dipper; a reinforced casting, forming the upper portion of the front, and constituting a juncture for the vest-shaped piece; and a plurality of metal vertical ribs, attached to the back of the dipper, to constitute means of attachment, and to constitute a reinforcement for the back. 5
3. In an excavating dipper, the combination of: a vest-shaped piece to form the back, the two sides and the front of the dipper; and a Y-shaped casting, forming the upper portion of the front, and constituting a juncture for the vest-shaped piece, and having bent-around portions for the reinforcement of a portion of the upper part of the sides. 10
4. In an excavating dipper, the combination of: a vest-shaped piece to form the back, the two sides and the front of the dipper; and a Y-shaped casting, forming the upper portion of the front, and constituting a juncture for the vest-shaped piece. 15
5. In an excavating dipper, the combination of: a vest-shaped piece to form the back, the two sides and the front of the dipper; and a reinforced wedge-shaped casting, forming the upper portion of the front, and constituting a juncture for the vest-shaped piece, and having bent-around portions for the reinforcement of a portion of the upper part of the sides. 20
6. In an excavating dipper, the combination of: a vest-shaped piece to form the back, the two sides and the front of the dipper; and a reinforced wedge-shaped casting, forming the upper portion of the front, and constituting a juncture for the vest-shaped piece. 25
7. As a new article of manufacture, a single integral reinforced substantially triangular dipper-front casting, having at its upper edge, i. e. the edge furthest from its lower vertex, means for the attachment of digging teeth, and having at each of its two upper vertices bent-around portions for the reinforcement of the upper part 30 of the sides of the dipper to which it is to be attached. 35
8. As a new article of manufacture, a single integral reinforced substantially triangular dipper-front casting, having at its upper edge, i. e. the edge furthest from its lower vertex, means for the attachment of digging teeth. 40
9. In an excavating dipper, the combination of: a vest-shaped piece to form the back, the two sides and the front of the dipper; a Y-shaped casting, forming the upper portion of the front, and constituting a juncture for the vest-shaped piece, and having non-abutting bent-around portions for the reinforcement of a portion of the upper part of the sides, these bent-around portions having forward and downward abutments; and two bail-lugs, each having provision for attachment to the dipper, and each having rearward and upward cooperating abutments. 45
10. In an excavating dipper, the combination of: a vest-shaped piece to form the back, the two sides and the front of the dipper; a Y-shaped casting, forming the upper portion of the front, and constituting a juncture for the vest-shaped piece, and having non-abutting bent-around portions for the reinforcement of a portion of the upper part of the sides, these bent-around portions having forward and downward abutments; two bail-lugs, each having provision for attachment to the dipper, and each having rearward and upward cooperating abutments; the dipper 50
- sides, the bent-around portions of the front, and the bail-lugs, having aligned holes for the insertion of shear-plugs; and two shear plugs, inserted through these holes and welded to one of the said three elements. 55
11. As a new article of manufacture, a single integral Y-shaped dipper-front casting, having at its upper edge means for the attachment of digging teeth, and having at its top sides bent-around portions for the reinforcement of the upper part of the sides of the dipper to which it is to be attached, these bent-around portions being provided with forward and downward abutments, appropriately adapted to receive cooperating abutments of bail-lugs. 60
12. In an excavating dipper, the combination of: sides; a lip-piece, having bent-around portions, overlapping the sides, these bent-around portions having forward and downward abutments; and two bail-lugs, each having provision for attachment to the dipper, and each having rearward and upward abutments cooperating respectively with the forward and downward abutments already mentioned. 65
13. In an excavating dipper, the combination of: sides; a lip-piece, having bent-around portions, overlapping the sides, these bent-around portions having forward and downward abutments; two bail-lugs, each having provision for attachment to the dipper, and each having rearward and upward abutments cooperating respectively with the forward and downward abutments already mentioned; the dipper sides, the bent-around portions of the front, and the bail-lugs, having aligned holes for the insertion of shear-plugs; and two shear plugs, inserted through these holes and welded to one of the said three elements. 70
14. In an excavating dipper, the combination of: the dipper proper, having on each side forward and downward abutments; and two bail-lugs, each having provision for attachment to the dipper, and each having rearward and upward abutments cooperating respectively with the forward and downward abutments already mentioned. 75
15. In an excavating dipper, the combination of: the dipper proper, having on each side forward and downward abutments; two bail-lugs, each having provision for attachment to the dipper, and each having rearward and upward abutments cooperating respectively with the forward and downward abutments already mentioned; the dipper sides and the bail-lugs, having aligned holes for the insertion of shear-plugs; and two shear plugs, inserted through these holes and welded to the dipper sides. 80
16. As a new article of manufacture, a single integral reinforced substantially triangular dipper-front casting, having at its upper edge, i. e. the edge furthest from its lower vertex, means for the attachment of digging teeth, having at each of its two upper vertices, bent-around portions for the reinforcement of the upper part of the sides of the dipper to which it is to be attached, and having a latch-keeper in its lower vertex. 85
17. As a new article of manufacture, a single integral reinforced substantially triangular dipper-front casting, having at its upper edge, i. e. the edge furthest from its lower vertex, means for the attachment of digging teeth, and having a latch-keeper in its lower vertex. 90
